UNITED STATES PATENT OFFICE.

PAUL KUNIN, OF MINNEAPOLIS, MINNESOTA.

HAIR-CURLING APPARATUS.

Application filed October 5, 1925. Serial No. 60,448.

This invention relates to apparatus for treating and curling hair and more particularly to a device for giving permanent waves upon human hair.

- 5 It is an object of this invention to provide in apparatus for curling hair, improved curling units adapted to be utilized in connection with any standard type of supporting bracket and adjusting mechanism.
- 10 Another object of the invention is to provide a highly efficient heating unit flexibly and adjustably supported from said bracket including a tubular housing, a curling rod insertable therein and highly efficient means
- 15 for retaining and centering said rod within said housing and means for protecting the hair and scalp treated in the process of effecting permanent waves.

A more specific object of the invention is 20 to provide hair curling apparatus comprising a depending chandelier having means for guiding and adjustably supporting a plurality of heating units connected thereto by means of flexible electric conductors, whereby 25 said heating units, in depending position, will be disposed in a figure encircling the head of the person to be treated and will not tend to become tangled with each other.

A still further object in such apparatus is 30 to provide a plurality of heating devices, each comprising a tubular casing, a curling rod carrying a protective shield at its lower end and efficient means for centering and retaining the upper and lower ends of said rod within said casing.

These and other objects of the invention will be apparent from the following description made in connection with the accompanying drawings, wherein like characters refer 40 to similar parts throughout the several views, and in which,

Fig. 1 is a fragmentary vertical section of the apparatus showing portions of the upper and lower brackets, with one of the heating devices operatively connected thereto;

Fig. 2 is a vertical section of the preferred form of heating device employed in the apparatus;

Fig. 3 is a bottom view of the same;

Fig. 4 is a plan view of the blank for forming the resilient retaining socket of the preferred form of the heating device; and

Fig. 5 is a fragmentary vertical section of the lower portion of a modified form of the heating device.

55

Referring to the drawings, a radial arm 12 of an overhead support is illustrated carrying at its outer end a trough-like frame member 13 in which a plurality of electric sockets 14 are housed and secured, the contacts of said sockets being accessible from the bottom of trough 13. Sockets 14 are connected to a source of electricity, suitable switches (not shown) being provided, and a pilot light 15^a is also carried by arm 12 connected in circuit with said socket to indicate whether or not said circuit is closed or open. A detachable cover plate 16 closes the top of trough member 13 and arm 12.

Disposed above the supporting bracket is 70 a bracket having radially extending arms 17 carrying suitable guide members 18 and 19 having oppositely aligned radially arranged apertures therethrough, through which cords or flexible connections 22^a are passed, the outer ends of said connections being secured to electrical connections 20 which connect the sockets 19 with the heating or curling devices. Counterweights 22 are secured to the inner falls of flexible members 22^a 85 adapted to balance said heating devices in desired positions. On the peripheral edge of trough members 13 resilient U-shaped retaining clips 23 are secured, each adapted to engage one of the heating devices to retain 90 the same in compact inoperative position.

The preferred form of heating devices, as illustrated in Figs. 1 to 4, inclusive, comprises an elongated tubular casing 25 having seated within its upper or inner end a resilient socket or retaining member 26 formed, preferably, from a blank, as illustrated in Fig. 4. A cap member 27, preferably of some compressible heat resistant material, such as cork, is disposed over the upper end 95 of the casing 25, holding the resilient socket 26 in proper operative position. Cap member 27 is provided at either side with a longitudinally extending slot 27^a in which the flexible electric connections 20 are disposed, 100 connections 20 passing through an annular spacer 28 secured about the intermediate portion of casing 25. The spacer 28 has secured thereto the upper end of a housing 29

enclosing a standard form of electric heating coil 30. The lower extremities of electric connections 20 are knotted below spacing member 28.

An elongated curling rod 31 is employed, adapted to have a strand of hair uniformly wound and secured thereon and having its upper or inner end, preferably, tapered or rounded and having a narrow retaining portion adapted to engage resilient socket 26 to center and releasably retain the rod 31 in proper operative position within the tubular casing 25. At the lower end of rod 31, a shield member 32 is secured, constructed of heat resistant material and adapted to close the lower or outer end of tubular casing 25, when the rod 31 is inserted therein in operative position. Shield member 32 has preferably the projecting plug portion adapted to fit snugly within the lower end of tube 25 to act as a stopper therefor and to center the lower end of rod 31. The plug portion of shield 32 is preferably recessed and secured to the lower end of rod 31 by means of a transverse pin. To permit a strand of hair, indicated by the letter X, to be curled on rod 31, a slot 32^a is formed in shield 32 extending from a peripheral edge thereof inwardly and having an enlarged mouth portion and a substantially round receiving portion. Obviously a strand of hair may be easily forced into the receiving portion of slot 32^a adjacent the scalp and retained therein and the free end of said strand may then be carefully wound on curling rod 31 and inserted in operative position within tubular casing 25. The shield member 32 is shown as equipped with a relatively small cleat 32^b secured to the under side thereof and adapted to retain a string or other flexible member α tied tightly around a strand of hair, thereby further securing the hair against longitudinal displacement when coiled on the rod 31.

It will, of course, be understood that the resilient socket 26 may be formed of a plurality of independent leaf springs or in any other suitable manner and that the shield member may be of other suitable forms, such as a stopper, and that a cleat or other string retaining means may be employed or dispensed with thereon, as desired, all within the scope of this invention.

In Fig. 5, a modified form of the heating device is shown, having the tubular casing 25 and a curling rod 33 adapted to be disposed therein, said curling rod rigidly carrying the shield 34 at its lower end. The shield and rod are secured to the lower or outer end of tubular casing 25 by means of a pair of leaf springs 35 secured adjacent the outer flanges of said shield, equipped with small retaining members 35^a adapted to engage notches or holes in the lower portion of tubular casing 25. In this form of the in-

vention, as in the preferred form, the lower portion of the curling rod is centered and held in operative position by mutually engaging parts on the lower end of the tubular casing and the shield member.

70

Operation.

In effecting permanent waves upon human hair, the person to be treated is disposed or seated beneath the bracket, with the axis of the head substantially centered thereunder. The heating devices are then released, as desired, from their retaining members 23 and depend in a figure encircling the head. Strands of hair are separated on the head and each strand is inserted adjacent the scalp through the slot 32^a in one of the shield members 32, the hair being further secured to the lower end of the curling rod 31, if desired, by means of the string α wound lightly thereabout and secured in the cleat 32^b. Each strand of hair having been treated with oil is then wound upon a curling rod 31 and the curl tightened by twisting said rod, as desired. The upper end of each strand is tightened or otherwise secured adjacent the upper end of rod 31 and the rod carrying the plug shield member 32 is then inserted within the tubular casing 25, the upper end of rod 31 thereby being engaged by the resilient socket 26 and centered and retained in operative position. The plug portion of shield 32 will also assist in centering and retaining the lower end of rod 31 to casing 25. The curling rod 31 may, of course, be employed within the scope of this invention without the plug-like shield carried at its lower end.

75

80

85

90

95

100

105

When the strands of hair, desired to be treated, are oiled and disposed within the heating devices, the electricity is turned on by means of the gang switches 14 and pilot lights 15, indicating whether or not its respective bank of heaters are on.

Obviously, the counterweights 22 permit the heating devices to be supported at a desired height for the respective strands of hair treated.

The novel structure of the improved heating devices greatly facilitate in efficiently causing permanent waves, inasmuch as the curling rod is longitudinally centered within tubular casing 25 and is securely retained therein. The cork cap members 27, having means for countersinking conducting wires 20, permit the operator to manipulate the several heating devices without injury to their hands, and the plug shields substantially close the ends of tubes 25 retaining the hot oil vapor therein.

110

115

120

125

From the foregoing description, it will be seen that the applicant has invented simple but highly efficient apparatus for curling human hair and effecting permanent waves thereon. The device has been put to actual 130

usage and has proved highly successful for all the purposes intended.

It, of course, will be understood that various changes and omissions may be made 5 in the form, details, proportions and arrangement of parts without departing from the scope of the invention.

What is claimed is:

1. In apparatus for curling hair, a heating device comprising a tubular heating chamber, a curling rod adapted to be disposed longitudinally within said heating chamber, a shield of dielectric material permanently carried by the outer end of said 15 curling rod and having a substantially cylindrical portion adapted to be forced into the outer end of said heating chamber to substantially close the same and center the outer end of said rod.

20 2. The structure set forth in claim 1, said shield having a slot therein extending from

the outer periphery thereof inwardly, through which a strand of hair may pass.

3. In apparatus for curling hair, a heating device comprising a tubular heating chamber, a curling rod adapted to be disposed longitudinally within said heating chamber, a shield of dielectric material permanently carried by the outer end of said curling rod and having a substantially cylindrical portion adapted to be forced into the outer end of said heating chamber to substantially close the same and center the outer end of said rod, said shield having a slot therein extending from the outer periphery thereof inwardly through which a strand of hair may pass, and means on the under surface of said shield by which a strand of hair may be secured to said shield and rod. 40

In testimony whereof I affix my signature.

PAUL KUNIN.
